UNDERGARMENT

Filed July 21, 1927

Inventor

H. V. Oldham

By *Lacey, Lacey*, Attorneys

UNITED STATES PATENT OFFICE

HENRY V. OLDHAM, OF McROBERTS, KENTUCKY

UNDERGARMENT

Application filed July 21, 1927. Serial No. 207,473.

This invention relates to underwear and more particularly to that designed for covering the upper part of the body, whether in the form of an undershirt, or a combined shirt and drawers, such as a union suit.

The invention provides a nether garment having a pad for covering and protecting the spinal column from drafts of air and sudden changes in temperature, said pad forming a part of the garment and extending from the tip to the root of the spinal cord and of a thickness to afford ample protection against climate conditions and prevent shock and undue pressure upon the spinal process and vertebra incident to impact with a non-yielding object.

While the drawing illustrates a preferred embodiment of the invention, it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is a front view of a nether garment of the type combining a shirt and drawers embodying the invention, parts being broken away, and the front open to expose the reinforced and padded back.

Figure 2 is an enlarged sectional view on the line 2—2 of Figure 1.

Figure 3 is an enlarged detail sectional view on the line 3—3 of Figure 1.

Corresponding and like parts are referred to in the following description and designated in the several views of the drawings by like reference characters.

While the invention is shown applied to a union suit, it is to be understood that it may be applied to an undershirt, whether combined with the drawers or separate and independent thereof. The invention resides in reinforcing and padding the back, so as to cover and protect the spinal cord and parts associated therewith, thereby preventing

drafts of air and changes in temperature from affecting the spinal column, while at the same time preventing pressure or impact upon the spinal column from producing any ill effects. As indicated most clearly in Figure 1 of the drawings the pad or reinforcement is long and narrow and disposed to extend over the regions of the spinal column, and this pad forms part of the garment and is stitched thereto, so as to extend from the tip to the root of the spinal column. The numeral 1 designates the back portion of the garment which may be of any usual material depending upon the season of the year. The pad or reinforcement preferably comprises a plurality of strips 2 and 3, which are approximately of the same length, but which vary in width. These strips are stitched to one another and to the back portion of the garment, the stitching coinciding with the marginal edges of the respective strip and with a medial longitudinal line.

The several lines of stitching pass through the strips and the material comprising the garment, as indicated most clearly in Figures 2 and 3 of the drawings. The body of the garment may be of any weight or determinate material and the parts may consist of wool or other material as found most advantageous. The thickness of the parts may be determined by the number of strips or the nature of the material employed. The central longitudinal portion of the pad is thick and decreases in thickness from a medial longitudinal line towards opposite longitudinal edges. In this manner the central portion of the pad in direct line with the spinal column affords a maximum protection against drafts of air, impact and pressure. The pad extends from the neck opening to a point adjacent the waist line, so as to cover the spinal column.

Many ailments are attributable to exposure of the spinal column so as to be affected by drafts of air, changes in temperature and by impact or pressure of an object thereagainst. The provision and location of the pad in the manner specified protect the spinal column and prevent lumbago, rheumatism and other ailments attributable to exposure of that portion of the human anatomy adjacent the

spinal column which is the nerve center and susceptible to air drafts, and shock incident to impact and pressure.

When the neck opening of the undershirt, or like nether garment is high, a reinforcement 4 is provided at the top of the back pad and is inset therein, thereby reinforcing the garment and providing an auxiliary pad for the back of the neck opposite the tip of the spinal cord.

The salient feature is the protection of the spinal column and since the present invention accomplishes this object very effectually, the undergarment may be lighter in weight than would otherwise be worn, thus permitting, without jeopardizing the health, the use of a very light garment in the spring and fall and a not heavy garment in winter, except perhaps in very severe climates, in which circumstance the usual heavy garments augmented, as in the present invention, may be worn.

Having thus described the invention, I claim:

In combination with an undergarment, a protective pad for the spine applied to the inner face of the back of the garment intermediate the width thereof and extending longitudinally thereof to cover the spinal column, said pad comprising a strip of fabric disposed flat against the garment longitudinally thereof, a second strip fitting flat against the first strip and of appreciably less length and width than the first strip and together with the first strip forming a pad having a thick medial longitudinal portion and decreasing in thickness towards its ends and side edges, and a sheet extending from the upper edge of the back of the garment and having its lower edge contacting with the upper edge of the second-mentioned strip.

In testimony whereof I affix my signature.

HENRY V. OLDHAM. [L.S.]
